UNITED STATES PATENT OFFICE.

THEODORE J. AMBERG, OF CHICAGO, ILLINOIS, ASSIGNOR TO AMBERG FILE AND INDEX COMPANY, A CORPORATION OF ILLINOIS.

GUIDE CARD FOR VERTICAL FILING SYSTEMS.

Application filed April 20, 1923. Serial No. 633,339.

The invention relates to improvements in guide cards and more particularly to guide cards for use in vertical filing systems. It has been common to provide guide cards with 5 tabs extending from one edge of the card on which tab is displayed the indicating or guide subject matter, but by reason of continual handling, such tabs frequently become bent or broken. It has also been suggested 10 to provide sheet metal tabs, but these for one reason or another have not proved satisfactory. According to my invention I provide guide cards with a suitable tab and then reinforce the same with a plate preferably of sheet metal, which plate not only 15 thoroughly reinforces the tab and holds it rigid with respect to the card, but also satisfactorily holds a removable indicating slip.

Further and more specific objects, features 20 and advantages will more clearly appear from the detail description given below taken in connection with the accompanying sheet of drawings which form a part of this specification. In the drawings Fig. 1 is a face 25 view of a guide or index card embodying my invention in the preferred form thereof.

Fig. 2 is an enlarged section taken on the line 2—2 of Fig. 1. Fig. 3 is an enlarged section taken on the line 3—3 of Fig. 1.

30 Referring to the drawings 4 represents the body portion of a suitable guide card preferably made of heavy strong cardboard or fiber board and 5 represents an integral guide or index tab projecting from the upper 35 edge thereof. The card may also be provided with a tab 6 on its lower edge provided with an eyelet 7 through which a suitable rod may be passed to hold or lock the same in the usual vertical filing cabinet.

40 8 represents a reinforcing plate preferably made of sheet metal extending from the body portion 4 of the card and over the tab 5, the upper edge of the plate being bent over the outer edge of the tab as at 9 to provide a depending flange 10 which is firmly pressed to the upper edge of the tab so as to grip the upper edge of the tab and firmly 45 secure the upper edge of the plate 8 to the upper edge of the tab. The plate 8 is also 50 rigidly secured to the body portion of the card directly opposite and below the tab 5 by riveting the same thereto as by means of eyelets 11. Opposite the tab 5 the plate 8 is bent or stamped outwardly as more clearly 55 shown in Fig. 2 at 12, so as to form a part

which is spaced from tab 5 and this part is provided with a window 13 so that a slot is formed between the stamped-out part and the card for displaying an indicating or guide slip 14 behind the plate. A strip of celluloid 60 15 may also be placed in the slot behind window 13 and in front of the indicating slip 14 in order to keep the latter clean. In order to prevent the removable transparent strip of celluloid 15 and the removable indicating slip 14 from slipping out of the space or slot behind the window, 13, I provide the plate 8 with projections 16, which 65 projections are adjacent the edges of the window and near the ends of the tab and 70 extend toward said tab or card. These projections are preferably stamped from the plate as shown in detail in Fig. 3 and, as 75 shown in Fig. 1, are narrower than the width of the slot, e. g. they extend substantially 80 across the slot only at the middle of the ends thereof, whereby by pressing the card away therefrom the index slip may be easily inserted past the projections, and yet the 85 projections satisfactorily prevent the index slip 14 and celluloid slip 15 from slipping out at either end of the pocket formed by the stamped-out part 12 of the reinforcing plate. However the projections have their outer 90 faces inclined at an angle to the face of the card and extending inwardly toward the card and laterally toward the window as shown in Fig. 3, this, with the resiliency of the card, permitting the indicating slip and celluloid strip to be readily inserted in the 95 slot past either of the projections but normally preventing the indicating slip and celluloid strip from slipping out past the projections although by pressing the card back away from either of the projections the celluloid strip and indicating slip may be slipped out past the projection.

By the arrangement shown the reinforcing plate is not only rigidly secured to the outer edge of the tab by being bent over and gripping the same, but is also rigidly secured to the body portion of the card opposite the tab and so does not depend for its reinforcing action upon a mere grip upon the edge of the card or tab, thus forming an exceptionally strong tab part. At the same time the reinforcing plate in combination with the tab provides a pocket with a window in which a suitable indicating slip may be removably secured. The 100 105 110

projections 16 prevent such indicating slip from accidentally falling out or accidentally being pushed out, although by slightly pressing the tab away from the reinforcing plate, 5 sufficient space will be provided between the projection 16 and the tab or card to permit the indicating slip to be pushed out and replaced by others, if so desired. It will also be noted that the stamped-out part 12 which 10 forms the slot for accommodating the indicating slip, and the window 13, extend below the top edge of the card and over part of the body portion of the card whereby a substantial portion of the indicating slip 15 will lie over the body portion of the card. This permits the use of a relatively wide indicating slip with a relatively narrow tab. It is advantageous to have a relatively narrow tab, i. e. one which projects from the 20 edge of the card only a short distance, as it is less likely to become broken and the card less likely to become injured in the manipulation of the file. However, by extending the indicating slip slot and window over the 25 body portion of the card, I am enabled to make use of a relatively narrow tab portion and at the same time use an indicating slip of the usual or any desired width.

While I have described my improvements 30 in great detail and with respect to a preferred form thereof, I do not desire to be limited to such details and form since many changes and modifications may be made and the invention embodied in widely different 35 forms, and I, therefore, desire to cover all forms and modifications coming within the scope or language of any one or more of the appended claims.

What I claim as new and desire to secure 40 by Letters Patent, is:

1. A guide card for vertical filing systems having an integral tab projecting from one of its edges and a reinforcing plate extending over said tab and secured with respect 45 thereto, said reinforcing plate having a stamped-out part spaced from the card forming a slot between the stamped-out part and the card to accommodate a removable indicating slip, said stamped-out part having a window for displaying the indicating slip and said stamped-out part having a projection at the end of the slot extending substantially across the slot between the stamped-out part and the card, said projection being narrower than the width of the 50 slot and permitting an indicating slip to be inserted into the slot past the projection, but normally preventing the indicating slip from slipping out past the projection.

2. A guide card for vertical filing systems having an integral tab projecting from one of its edges and a reinforcing plate extending over said tab and secured with respect thereto, said reinforcing plate having 55 a stamped-out part spaced from the card forming a slot between the stamped-out part and the card to accommodate a removable indicating slip, said stamped-out part having a window for displaying the indicating slip and said stamped-out part having a projection at the end of the slot extending substantially across the slot between the stamped-out part and the card, said projection being narrower than the width of the slot and permitting an indicating slip to be inserted into the slot past the projection, but normally preventing the indicating slip from slipping out past the projection.

3. A guide card for vertical filing systems having an integral tab projecting from one of its edges and a reinforcing plate extending over said tab and secured with respect thereto, said reinforcing plate having a stamped-out part spaced from the card forming a slot between the stamped-out part and the card to accommodate a removable indicating slip, said stamped-out part having a projection at the end of the slot extending substantially across the slot between the stamped-out part and the card, said projection having a face inclined at an angle to the face of the card and extending inwardly toward the card and laterally toward the window, thereby permitting an indicating slip to be inserted into the slot past the projection but normally preventing the indicating slip from slipping out past the projection.

3. A guide card for vertical filing systems having an integral tab projecting from one of its edges and a reinforcing plate extending over said tab and secured with respect thereto, said reinforcing plate having a stamped-out part spaced from the card forming a slot between the stamped-out part and the card to accommodate a removable indicating slip, said stamped-out part having a window for displaying an indicating slip and said stamped-out part having projections at each end of the slot, which projections extend substantially across the slot between the stamped-out part and the card, the resiliency of the card permitting an indicating slip to be inserted into the slot past either of the projections, while the projections normally prevent the indicating slip from slipping out past the projections.

4. A guide card for vertical filing systems having an integral tab projecting from one of its edges and a reinforcing plate extending over said tab and secured with respect thereto, said reinforcing plate having a stamped-out part spaced from the card forming a slot between the stamped-out part and the card, a removable indicating slip and a transparent celluloid strip removably located in said slot, said stamped-out part having a window for displaying the indicating slip through said celluloid strip and said stamped-out part having projections at the ends of the slot extending substantially across the slot between the stamped-out part and the card to normally prevent the celluloid strip and indicating slip from slipping laterally out of the slot.

5. A guide card for vertical filing systems, having an integral tab projecting from its top edge and a sheet metal reinforcing plate extending over said tab from the body portion of the card, said plate being bent over and gripping the outer edge of the tab and being secured to the body portion of the card below the tab, said reinforcing plate having a stamped-out part spaced from the card and forming a slot between the stamped-out part and the card, a removable indicating slip and a transparent celluloid strip removably located in said slot, said stamped-out part having a window for displaying the indicating slip through said celluloid strip and said stamped-out part having projections at the ends of the slot extending substantially across the slot between the stamped-out part and the card to normally prevent the celluloid strip and indicating slip from slipping laterally out of the slot.

- cating slip in said slot between the stamped-out part and the card, said stamped-out part having a window for displaying the indicating slip and said stamped-out part having a projection at the end of the slot, which projection is narrower than the width of the slot but extends substantially across the slot between the stamped-out part and the card to normally prevent the indicating slip from slipping out past the projection but permitting the indicating slip to be inserted in the slot past the projection. 45
5. A guide card for vertical filing systems, having an integral tab projecting from its top edge and a sheet metal reinforcing plate extending over said tab from the body portion of the card, said plate being bent over and gripping the outer edge of the tab and being secured to the body portion of the card below the tab, said reinforcing plate having a stamped-out part spaced from the card and forming a slot between the stamped-out part and the card, a removable indicating slip in said slot between the stamped-out part and the card, said stamped-out part having a window for displaying the indicating slip, said stamped-out part having means at each end of the slot for normally preventing the indicating slip from slipping laterally from the slot, one of said means comprising a projection at one end of the slot, said projection being narrower than the width of the slot but extending substantially across the slot, and being adapted to permit the indicating slip to be inserted into the slot between the stamped-out part and the card and past said projection, and also permitting the indicating slip to be slipped out of the slot past said projection upon pressing the card away therefrom. 50
6. A guide card for vertical filing systems, having an integral tab projecting from one of its edges and a reinforcing plate extending over said tab and secured with respect thereto, said reinforcing plate having a stamped-out part spaced from the card forming a slot between the stamped-out part and the card to accommodate a removable indicating slip, said stamped-out part having a window for displaying the indicating slip and said stamped-out part having means at each end of the slot for normally preventing the indicating slip from slipping laterally from the slot at least one of said means at one end of the slot being adapted however to permit the indicating slip to be inserted into the slot between the stamped-out part and the card and past said means. 55
7. A guide card for vertical filing systems, having an integral tab projecting from its top edge and a sheet metal reinforcing plate extending over said tab from the body portion of the card, said plate being bent over and gripping the outer edge of the tab and being secured to the body portion of the card below the tab, said reinforcing plate having a stamped-out part spaced from the card and forming a slot between the stamped-out part and the card, a removable indicating slip in said slot between the stamped-out part and the card, said stamped-out part having a window for displaying the indicating slip, said stamped-out part having means at each end of the slot for normally preventing the indicating slip from slipping laterally from the slot, one of said means comprising a projection at one end of the slot, said projection being narrower than the width of the slot but extending substantially across the slot, and being adapted to permit the indicating slip to be inserted into the slot between the stamped-out part and the card and past said projection, and also permitting the indicating slip to be slipped out of the slot past said projection upon pressing the card away therefrom. 60
8. A guide card for vertical filing systems, having an integral tab projecting from one of its edges and a reinforcing plate extending over said tab and secured with respect thereto, said reinforcing plate having a stamped-out part spaced from the card forming a slot between the stamped-out part and the card to accommodate a removable indicating slip, said stamped-out part having a window for displaying the indicating slip and said stamped-out part having means at each end of the slot for normally preventing the indicating slip from slipping laterally from the slot at least one of said means at one end of the slot being adapted however to permit the indicating slip to be inserted into the slot between the stamped-out part and the card and past said means. 65
9. A guide card for vertical filing systems, having an integral tab projecting from one of its edges and a reinforcing plate extending over said tab and secured with respect thereto, said reinforcing plate having a stamped-out part spaced from the card forming a slot between the stamped-out part and the card to accommodate a removable indicating slip, said stamped-out part having a window for displaying the indicating slip and said stamped-out part having means at each end of the slot for normally preventing the indicating slip from slipping laterally from the slot at least one of said means at one end of the slot being adapted however to permit the indicating slip to be inserted into the slot between the stamped-out part and the card and past said means. 70
10. A guide card for vertical filing systems, having an integral tab projecting from one of its edges and a reinforcing plate extending over said tab and secured with respect thereto, said reinforcing plate having a stamped-out part spaced from the card forming a slot between the stamped-out part and the card to accommodate a removable indicating slip, said stamped-out part having a window for displaying the indicating slip and said stamped-out part having means at each end of the slot for normally preventing the indicating slip from slipping laterally from the slot at least one of said means at one end of the slot being adapted however to permit the indicating slip to be inserted into the slot between the stamped-out part and the card and past said means. 75
11. A guide card for vertical filing systems, having an integral tab projecting from one of its edges and a reinforcing plate extending over said tab and secured with respect thereto, said reinforcing plate having a stamped-out part spaced from the card forming a slot between the stamped-out part and the card to accommodate a removable indicating slip, said stamped-out part having a window for displaying the indicating slip and said stamped-out part having means at each end of the slot for normally preventing the indicating slip from slipping laterally from the slot at least one of said means at one end of the slot being adapted however to permit the indicating slip to be inserted into the slot between the stamped-out part and the card and past said means. 80
12. A guide card for vertical filing systems, having an integral tab projecting from one of its edges and a reinforcing plate extending over said tab and secured with respect thereto, said reinforcing plate having a stamped-out part spaced from the card forming a slot between the stamped-out part and the card to accommodate a removable indicating slip, said stamped-out part having a window for displaying the indicating slip and said stamped-out part having means at each end of the slot for normally preventing the indicating slip from slipping laterally from the slot at least one of said means at one end of the slot being adapted however to permit the indicating slip to be inserted into the slot between the stamped-out part and the card and past said means. 85

In testimony whereof I have signed my name to this specification.

THEODORE J. AMBERG.
